UNITED STATES PATENT OFFICE

104,182

DESIGN FOR A WINCH OR THE LIKE

Isidore Bromfield, Brookline, Mass.

Application July 31, 1936, Serial No. 64,156

Term of patent 14 years

To all whom it may concern:

Be it known that I, Isidore Bromfield, a citizen of the United States, residing at Brookline, in the county of Norfolk and Commonwealth of Massachusetts, have invented a new, original, and ornamental Design for a Winch or the like, of which the following is a specification, reference being had to the accompanying drawings, forming a part thereof.

In the accompanying drawings, Figures 1 and 2 are photographic perspective views of the rear and the front elevation, respectively, of a winch showing my new design, and Figs. 3 and 4 are a top plan view and a view in end elevation, respectively, of the winch shown in Figs. 1 and 2.

I claim:

The ornamental design for a winch or the like, substantially as shown.

ISIDORE BROMFIELD.
